UNITED STATES PATENT OFFICE.

FREDERICK I. FRIEDLINE, OF LITTLE ROCK, ARKANSAS.

RADIAL CAR-PULLER SHEAVE.

No. 806,534.

Specification of Letters Patent.

Patented Dec. 5, 1905.

Application filed January 12, 1905. Serial No. 240,696.

To all whom it may concern:

Be it known that I, FREDERICK I. FRIEDLINE, of Little Rock, Pulaski county, Arkansas, have invented certain new and useful Improvements in Radial Car-Puller Sheaves, of which the following is a specification.

The object of this invention is to provide an apparatus by means of which power can be applied to draw a load or object from any direction to a certain fixed point, the device being generally used and particularly adapted for moving cars or loads from different directions to set them in a certain desired position for loading or unloading.

The invention consists generally in various constructions and combinations, all as hereinafter described, and particularly pointed out in the claims.

In the accompanying drawings, forming part of this specification, Figure 1 is a plan view of a radial car-puller embodying my invention. Fig. 2 is a side elevation of the same. Fig. 3 is an end view looking toward the edge of the sheaves. Fig. 4 is a vertical section showing the manner of mounting the oscillating sheave on its support.

In the drawings, 2 represents a plate of any suitable material, preferably metal, that forms the base or support for the sheave-housings.

3 is a fixed housing rigidly secured to the under side of the plate 2 and carrying a sheave 4.

5 is the housing for the upper sheave 6, that corresponds to the lower one and is mounted on the upper side of the plate 2 at the opposite end. A hole 7 is provided in the plate to receive a stud 8, having a flange 9 at its lower end and a central hole or opening 10. A collar 11 is provided on the housing 5 and adapted to fit over the upper end of the stud 8 and be securely fixed thereto by means of set-screws 12 or the threads, as shown, or both. This construction forms a pivot for the housing of the upper sheave, allowing it to make a complete revolution on the base 2. I prefer to provide lugs 13 on the housing 5, wherein antifriction-rollers 14 are mounted and adapted to rest and travel upon a flat curved track 15 on the surface of the base-plate 2. A cable 16 leads from a suitable source of power under the sheave 4 and vertically be-

tween it and the sheave 6, through the hole 10, and up over the sheave 6 to the load that it is desired to move. The oscillation of the upper sheave on its pivot will allow it to be revolved when the direction of the load changes.

The device is used with rope or wire cable car-pullers, the rope or cable leading out in any direction to the cars or load. It is usually placed on the ground beside the track with the cable leading out of the elevator or building, through the sheaves, and up or down the track to the cars.

I claim as my invention—

1. The combination, with a base-plate, of a housing rigidly secured to the under side thereof, a sheave mounted therein, a second housing pivotally supported on the upper side of said base, a sheave carried by said second housing, and a cable for said sheaves.

2. The combination, with a base-plate, of a housing having a suitable sheave secured to one side thereof, a second housing, a hollow stud pivoted in said base-plate and wherein said second housing is secured on the side of said plate opposite from said first-named housing, a sheave for said second housing, and a cable for said sheaves.

3. A radial car-puller comprising a plate, a housing rigidly secured to one side thereof and having a suitable sheave, a hollow stud having a flanged lower end loosely fitting within a hole in said plate, a second housing adjustably secured to said stud on the side of said plate opposite from said first-named housing said second housing being free to revolve with said stud and having a suitable sheave, and a cable extending from a suitable source of power and passing under said first-named sheave and through said hollow stud and up over said second sheave to the load, substantially as described.

4. The combination, with a base-plate, of sheaves mounted on the upper and under sides thereof, and one of said sheaves being swiveled, substantially as described.

In witness whereof I have hereunto set my hand.

FREDERICK I. FRIEDLINE.
